(57) **CLAIM**

I claim the ornamental design for a waste receptacle, as shown and described.

DESCRIPTION

FIG. 1 is a perspective view of a waste receptacle according to the embodiment of the present invention;

FIG. 2 is a front view of the waste receptacle of FIG. 1, the rear view being a mirror image thereof;

FIG. 3 is a left side view of the waste container shown in FIG. 1, the right side being a mirror image thereof;

FIG. 4 is a top plan view of the waste receptacle shown in FIG. 1; and,

FIG. 5 is a bottom view of the waste receptacle shown in FIG. 1.

The broken lines shown herein are for illustrative purposes only and form no part of the claimed design.
